US00D832366S

(12) **United States Design Patent** (10) **Patent No.:** **US D832,366 S**
(45) **Date of Patent:** **** Oct. 30, 2018**

(54) **TOY CONNECTOR**

(71) Applicant: **Box Tiles LLC**, Highland Park, IL (US)

(72) Inventors: **Noah J. Ornstein**, Highland Park, IL (US); **Joseph M. Kelley**, Highland Park, IL (US)

(73) Assignee: **Box Tiles LLC**, Highland Park, IL (US)

(**) Term: **15 Years**

(21) Appl. No.: **29/609,362**

(22) Filed: **Jun. 29, 2017**

(51) LOC (11) Cl. **21-01**

(52) U.S. Cl.

USPC **D21/486**; D8/382

(58) **Field of Classification Search**

USPC D21/484, 485, 486, 488, 489, 491, 494, D21/495, 499, 500–504; 446/69, 85, 446/102–128; D8/382

(57) **CLAIM**

We claim the ornamental design for a toy connector, as shown and described.

DESCRIPTION

FIG. 1 is a top perspective view of the toy connector in accordance with a first embodiment of our new design;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top perspective view of the toy connector in accordance with a second embodiment of our new design;

FIG. 10 is a bottom perspective view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a right side elevation view thereof; and,

FIG. 16 is a left side elevation view thereof.

The broken lines illustrate portions of the toy connector that form no part of the claimed design.

The oblique shade lines in FIGS. 9–16 represent a transparent or translucent surface and not surface ornamentation.

1 Claim, 10 Drawing Sheets
